UNITED STATES PATENT OFFICE.

WILLIAM PATZER, OF MERIDEN, CONNECTICUT, ASSIGNOR TO THE MERIDEN BRONZE COMPANY, OF SAME PLACE.

LAMP-STANDARD.

SPECIFICATION forming part of Letters Patent No. 373,303, dated November 15, 1887.

Application filed April 18, 1887. Serial No. 235,139. (No model.)

To all whom it may concern:

Be it known that I, WILLIAM PATZER, of Meriden, in the county of New Haven and State of Connecticut, have invented a new Improvement in Lamp-Standards; and I do hereby declare the following, when taken in connection with accompanying drawings and the letters of reference marked thereon, to be a full, clear, and exact description of the same, and to which said drawings constitute part of this specification, and represent, in—

Figure 1, a side view of a complete standard and lamp; Fig. 2, a vertical central section of the two tubes and the adjusting mechanism 15 enlarged; Figs. 3 and 4, modifications in the adjusting mechanism.

This invention relates to an improvement in standards for that class of lamps which consist of a base adapted to stand upon the floor and 20 the standard made adjustable to set the lamp to different elevations.

The object of this invention is the construction of an engaging device between the two parts of the standard, whereby the standard 25 may be readily adjusted, yet securely held at any desired position and without liability of the movable part accidentally sliding downward.

A represents the outer tube, which is supported vertically in the base in the usual manner, and so as to be stationary. B represents the inner tube, which is of a diameter substantially corresponding to the internal diameter of the outer tube, and so as to slide freely up 35 and down. In the lower end of the tube B a cam, C, is hinged at one side, as at a, and extends across the tube to the opposite side, and so as to bear upon that side of the inner tube, as seen in Fig. 2. The length of the cam from 40 the pivot to the free end is somewhat greater than the actual distance from that bearing-point to the inside of the outer tube, and so that the cam, while its free end bears upon the opposite side, will stand in an oblique position—that is, its free end will be lower than its 45 hinged point—hence in that condition any tendency to force the inner tube downward will only cramp the cam against the inside of the outer tube and prevent descent of the inner tube; yet as the inner tube is raised it will

lift the hinge-point first, and so that the free end will readily slide upward without any considerable amount of friction, thus permitting a free upward movement of the inner tube, but the tube is cramped against downward movement. 55

Within the tube B is a suitable spring, D, adapted to hold the cam upward to its cramping position, but yield for the free upward movement, as before described. Within the 60 inner tube is a vertical rod, E, which rests upon the upper surface of the cam at a point distant from its pivot, and extends upward through the tube B. At some point near the upper end of the tube B a collar, F, is fixed 65 to the tube, and this is best made at the termination of the tube, and at the point where the lamp is secured, as seen in Fig. 1. Transversely in this collar a slide, G, is arranged, extending outward through the collar at one 70 side, provided with a suitable head, against which the thumb may be placed. This slide upon its under side is made inclined, or of cam shape, as at b. The rod E extends upward, so that while its lower end rests upon 75 the cam its upper end will stand beneath the incline b of the slide G, the rod being held up by the spring of the cam.

If the slide G be pressed inward, as indicated in broken lines, Fig. 2, the incline b will 80 force the rod E downward and correspondingly turn the cam, as indicated in broken lines, so as to take the cam out of engagement with the inside of the outer tube. Then, while holding the slide G thus pressed inward and 85 the cam downward, the inner tube may be lowered or raised to any desirable extent without engagement between the cam and the inner tube, thus leaving the inner tube free for any required adjustment; but so soon as the 90 thumb is removed from the slide G, then the spring C reacts, brings the cam to its bearing, forces the rod E upward, and the rod, acting against the incline on the slide, forces the slide outward to its normal position, so that as soon 95 as the slide G is released the cam comes into immediate action; hence the inner tube can only move downward so long as the slide G is held inward, depressing the cam.

Instead of the radial or transverse slide G 100

to operate the cam, it may be done by a lever, as seen in Fig. 3, adapted to bear upon the upper end of the rod, so that by pressing the lever downward, as seen in broken lines, the rod 15 will be forced downward, and the cam released accordingly, the spring when free reacting to bring the lever to its up position. I however prefer the transverse slide.

The rod and slide may be omitted, as seen 10 in Fig. 4; but in this case the cam must be adjusted so as to bear against the inside of the outer tube only with sufficient force to hold the outer and inner tubes in engagement, and so that sufficient power being applied to the tube B to force it downward, the cam will 15 slide upon the inner surface of the outer tube, the spring holding the cam up to its engagement with the outer tube, but so as to leave it free to slide when the inner tube is drawn upward.

I claim—

1. The combination of the outer tube, A, the inner tube, B, vertically adjustable in the outer tube, the cam C, hung at one side of the inner tube upon an axis at right angles to the 25 axis of the tube and extending across the in-

ner tube to the opposite side, but in a downwardly-inclined direction, and of a length that its free end may bear against the inner surface of the outer tube, a rod within the inner tube, its lower end adapted to bear upon the said cam, and a bearing-piece arranged transversely across the inner tube above said rod and so as to bear upon its upper end, the said bearing-piece extending radially outside said inner tube, with a spring between said cam and inner tube, the tendency of which is to lift the cam, all substantially as described. 35

2. The combination of the outer tube, A, the inner tube, B, the cam C, hung in the lower end of the inner tube, a spring between the inner tube and cam, a rod extending from the cam upward within the inner tube, and a transverse slide, G, in the upper end of the inner tube, having its under face inclined, and against 40 which incline the upper end of the said rod rests, substantially as described.

WILLIAM PATZER.
